UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed February 18, 1920. Serial No. 359,684.

To all whom it may concern:

Be it known that I, WINFRED T. POWELL, a citizen of the United States, residing at Rochester, in the county of Monroe and

5 State of New York, have invented certain new and useful Improvements in Automatic Telephone Systems, of which the following is a full, clear, concise, and exact description.

10 This invention relates to telephone systems, and more particularly to telephone systems employing automatic switching in establishing a conversational connection between the calling and called subscribers.

15 It is the purpose of the present arrangement to provide means whereby the talking connection is extended through the operation of the trunking switch individual to each of the lines. This result is achieved 20 by the use of relatively simple registers for storing the designation of the wanted line, which thereupon operate to cause the calling and called trunk selecting switches to complete a connection.

25 Figs. 1, 2 and 3 of the drawings when placed in the order named diagrammatically represent a portion of the telephone system in which the portion of Fig. 1 above the dotted lines, represents the operating circuits of one line switch or trunk selecting switch, herein designated the calling line switch, while the portion of the drawing at the bottom of Fig. 1 below the dotted lines, diagrammatically represents the operating

30 circuits of a second line switch or trunk selecting switch of a line herein designated the called line. The portion of Fig. 1 between the dotted lines represents what are herein called link circuits or trunk circuits.

40 At the upper left hand corner of Fig. 2 there are shown the control relays individual to one of the link circuits previously mentioned. At the center portion of Figs. 45 2 and 3, there is shown within the dotted rectangle, an allotter which functions to select idle link circuits in consecutive order. At the bottom of Figs. 2 and 3 there are shown within the two dotted rectangles, devices herein referred to as the tens register and the units register, and when taken to-

gether these two registers are called a sender. There may be as many of these senders as are necessary to care for the number of calls that are being 55 simultaneously established. At the upper right hand corner of Fig. 3 there is shown a set of ten relays for the whole exchange, each of the relays being provided with ten sets of contacts.

60 Fig. 4 shows the circuits of the register sender modified so that the group of ten multi-contact relays may be replaced by a multi-brush rotary switch.

65 In the system herein disclosed there are one hundred lines which have access to any one of ten link circuits. Five senders, each provided with a tens and units register cooperate in the extension of telephone calls, and as soon as a telephone connection is 70 completed, these register senders revert to common use. By reference to Fig. 1, it will be noted that the line switch or trunk selecting switch individual to each line, is provided with twenty-five contacts. Five 75 of these contacts lead to the register senders, and ten of these contacts are connected to the outgoing end of a link or trunk, while the other ten contacts are connected to the incoming end of the trunk or link circuit. 80

85 It will be seen that on the initiation of a call, the line switch individual to the calling line selects any one of five senders if idle. The calling subscriber thereupon operates his dial sender to transmit impulses corresponding to the designation of the wanted line. These impulses are stored up in the registers of the register sender and when a number is thus stored up, the line switch of the called line is started to operate 90 and continues to advance its brushes until the incoming end of a previously allotted link circuit is located. Thereupon the sender is released and the calling line switch hunts for the outgoing end of the same 95 link circuit. The allotter then advances to assign another idle trunk for the use of the next calling line. In this brief description of the system no mention has been made of the ringing or busy signal operations, but 100 these will take place as will be hereinafter pointed out.

The structure of the line or trunk selecting switches, allotter and registers and other progressively operable switches employed in the system may be substantially similar to that disclosed in the patent to Clement, #1,107,153, patented August 11, 1914. The number of brushes and sets of contacts with which these brushes co-operate, vary in number in the different switches as will appear by reference to the drawings. As herein disclosed the operating circuits of the line switch are arranged so that this switch remains in engagement with the trunk or link circuit last used. It will be understood, however, that a switch which advances to normal or restores to normal may be employed without departing from the spirit of the present invention.

It is believed that the invention will best be understood by tracing the method of establishing a connection from a calling substation, such as A, to a called substation, such as that designated B. When the calling subscriber at A removes his receiver from its switchhook, an operating circuit is closed for the line relay LR, from grounded battery, lower winding of this relay, continuity contact and spring 5 of the cut-off relay CO, through the substation circuits of the calling subscriber, continuity spring and contact 6 of the cut-off relay to ground. The line relay LR attracts its armatures and thereby completes an operating circuit for the motor magnet MM of the trunk selecting switch individual to the calling line. The operating circuit of the motor magnet MM extends from grounded battery, resistance, back contact, armature and winding of the motor magnet MM, conductor 7, inner-most armature and front contact of the line relay LR, conductor 8, continuity spring and contact 6 of the cut-off relay to ground.

Under the control of this last described circuit, the motor magnet MM continues to advance the brushes of the line switch until the sender test brush of the line switch engages the test terminal of a link circuit connected to an idle sender. As soon as the sender test brush locates such an idle sender, a circuit is closed for shunting the motor magnet MM and for operating the cut-off relay CO. Such circuit extends from grounded battery, resistance, back contact and armature of the motor magnet MM, upper winding of the cut-off relay CO, conductor 9, upper-most armature and front contact of line relay LR, left hand armature and back contact of slow releasing relay 10, sender test brush 11, and since it has been assumed that the first idle sender located by the sender test brush 11 is that sender individual to the test contact 12 and test conductor 13, conductor 14, back contact, armature of relay 15, conductor 16, brush

17 of the units register in its normal position, conductor 18, brush 19 of the tens register in its normal position, left hand contact and armature of the slow releasing relay 20 and back contact and armature of impulse relay IMP to ground. As soon as the motor magnet MM is thus short circuited, it ceases to advance the switch, and the cut-off relay CO when operated disconnects the line relay LR from the line so that this relay thereupon de-energizes and extends the calling line through its upper armatures and continuity springs to the tip brush 21 and ring brush 22 of the line switch.

When the cut-off relay CO is operated, it closes a locking circuit for itself from ground through its lower winding and in multiple therewith a circuit from ground, left hand winding of relay 10, armature and front contact of the cut-off relay CO, through the holding brush 23, holding contact 24, holding conductor 25, back contact and armature of relay 33, and relays 10 and 15 are operated in this circuit, and relay 15 is held operated in series, and relay 10 in multiple with the cut-off relay CO. The relay 15 attracts its armatures and at its right hand armature and front contact closes a circuit completed from ground, left hand armature and back contact of relay 39, front contact and armature of relay 15, conductor 45, and winding of slow releasing relay 26 to grounded battery. The relay 26 is operated and prepares a substitute energizing circuit for the relay 15 independent of the outer right hand armature of relay 33.

As soon as the calling subscriber's line is extended through to the brushes 21 and 22 which at this time are in engagement with the contacts 27 and 28, an energizing circuit is completed for the impulse relay IMP of Fig. 2. This circuit extends from ground, through the left hand winding of relay IMP, conductor 29, contact 27, and thence over the circuit previously described over brush 21 to the substation A, and then to ring brush 22 and contact 28, conductor 30, right hand winding of relay IMP, conductor 31, lower winding of resistance unit 32 to grounded battery. The relay IMP is energized in this circuit, and attracts its armature to close an operating circuit for the slow releasing relay 20. The sender is now in condition to receive the impulses corresponding to the tens designation of the wanted subscriber's line. The calling subscriber thereupon operates his impulse sender to transmit impulses corresponding to the called subscriber's line. Let it be assumed that this number designation is 89. The calling subscriber first sends eight impulses caused by eight interruptions of the circuit just described to the impulse relay 130

IMP. This last named relay thereupon vibrates its armatures one for each interruption of its operating circuit, and in response to each of these impulses an operating circuit is closed for the motor magnet MM of the tens register, from grounded battery, winding of this magnet, left hand back contact and armature of relay 33, front contact and armature of slow releasing relay 20, back contact and armature of impulse relay IMP to ground. The slow releasing change-over relay 36 is also actuated in a circuit in multiple of that just described.

In response to each operation of the motor magnet MM, the brushes 19 and 34 of the tens register are advanced one step, and after the receipt of eight impulses, the brush 34 will be in engagement with contact 35. At the close of the tens series of impulses relay IMP will attract its armature for a relatively long interval, so that the energizing circuit of the slow releasing relay 36 is interrupted for a long enough time to permit this relay to extend the control of the impulse relay IMP to the units register. This is effected, as follows:—As soon as relay 36 de-energizes, it closes a circuit from ground, through its armature and back contact, continuity spring and contact 37 and winding of the switching relay 33, brush 19 of the tens register and the contact with which it is in engagement, back contact, armature and winding of the motor magnet MM to grounded battery. The switching relay 33 is energized in this circuit and closes a locking circuit for itself from ground, through its armature and continuity spring over the circuit just described to grounded battery, through the winding of the motor magnet MM. The motor magnet will not operate in series with relay 33. The next series of impulses will now be repeated through the left hand front contact and armature of switching relay 33, through the motor magnet of the units register. The calling subscriber thereupon operates his dial sender to transmit nine impulses corresponding to the units digit of the wanted number and in response to each of these impulses the relay IMP retracts its armature, thereby closing a circuit from ground, through the armature and front contact of relay 20, left hand armature and front contact of relay 33, conductor 38, inner armature and back contact of relay 39, conductor 40, winding of the motor magnet MM of the units register to grounded battery. Under the control of this circuit the motor magnet MM of the units register advances its brushes nine steps, and places the brush 41 in engagement with contact 42. When the slow releasing relay 36 releases at the close of the units series of impulses, a circuit is closed from ground, its armature and back contact, conductor 43, winding of relay 39, conduct-

tor 18, units register brush 17, back contact, armature and winding of motor magnet MM to grounded battery. The motor magnet MM will not operate in series with relay 39. The relay 39, however, is energized and attracts its armature, closing a locking circuit for itself from ground, its armature, front contact and winding to battery over conductor 18. The original energizing circuit of relay 26 is opened at relay 39, but relay 26 is now locked energized over a circuit closed from grounded battery, winding of relay 26, conductor 45, armature and front contact of relay 15, left hand back contact and armature of relay 46, conductor 51 and upper-most front contact and armature of relay 26 to ground. At this time the relays IMP 20, 33, 15, 39 and 26 are standing operated.

The designation of the wanted line has thus been stored in the register sender, and the designations of other wanted lines may be similarly stored on the four other senders. It is essential that the calls indicated by these designations be completed, one at a time, and for this purpose an extended starter wire is provided, although it will be understood that a rotary switch may be employed to accomplish this result. The extended starter wire, of the present arrangement extends from grounded battery, upper winding of resistance unit 32, winding, armature and back contact of the motor magnet MM of the allotter, back contact and armature of relay 50, conductor 125, continuity spring and armature of relay 39, conductor 48, inner-most armature and front contact of relay 26, conductor 47, right hand winding of relay 46 to ground. When relay 46 is energized and when the designation of the wanted line is stored up on this sender these devices are effective through the co-operation of the group of multi-contact relays to start the operation of the wanted line switch. As soon as the relay 39 of the units register of the first sender in the series de-energizes, which takes place when the call is completed, the starter wire will now be extended and a circuit is closed from grounded battery, upper winding of resistance unit 32, winding, armature and back contact of the motor magnet MM of the allotter, armature and back contact of relay 50, conductor 125, continuity spring and contact 49, conductor 115, to a continuity spring similar to 49 and an armature of the relay similar to 39 at the second sender, a conductor similar to 48, inner-most armature and front contact of a relay similar to 26, a conductor similar to 47, and the right hand winding of a relay similar to 46 to ground. The operation of the relay 46 at the second sender will make the designation stored up in that sender effective to bring about the operation of the group of multi-contact relays, 130

and in turn initiate the operation of the wanted line switch. In like manner when the first and second senders are idle, the designation stored up in the third sender 5 will become effective to bring about the completion of a call.

- It is assumed that the allotter is standing in a position to designate an idle link circuit under which assumption the relay 46 10 is operated in a circuit traceable from ground, right hand winding of this relay, conductor 47, inner-most upper front contact and armature of relay 26, conductor 48, outer armature and continuity spring 49 15 of relay 39, back contact and armature of relay 50, back contact, armature and winding of the motor magnet MM of the allotter, and upper winding of the resistance unit 32 to grounded battery. The relay 46 20 on operation closes a locking circuit for itself from grounded battery, through its left hand winding, front contact and armature, conductor 51, upper-most front contact and armature of relay 26 to ground. As 25 soon as relay 46 is operated, it interrupts the holding circuit of relay 26, but this last mentioned relay is slow releasing, so that the holding circuit for relay 46 is held operated for a short time. While relay 46 is operated, it extends a circuit from 30 ground, its inner armature and front contact, conductor 52, register brush 34, its contact 35, conductor 53, multi-contact relay 54 to grounded battery. The relay 54 35 is energized in this circuit and closes its ten contacts. Simultaneously a second circuit is closed from ground, inner armature and front contact of relay 46, conductor 55, left hand winding of relay 56, units register brush 41, now in engagement with contact 42, conductor 57, closed contact 58, conductor 59, contact 60 and armature of the cut-off relay CO' of the wanted line B, conductor 61, and upper winding of slow releasing relay 62, conductor 72, and winding of relay 71 to grounded battery. The relays 71, 62 and 56 are operated in this circuit. The relay 56 completes a locking circuit for itself from grounded battery, winding of the motor magnet MM of the units 45 register, its armature and back contact, brush 17, right hand winding, front contact and armature of relay 56, conductor 63, winding of relay 64, allotter brush 65, back 50 contact and armature of relay 67, and back contact and armature of relay 68 to ground. The relay 46 has also completed a circuit from ground, its outer armature and front contact, right hand winding of relay 60 50 to grounded battery. The relay 50 attracts its armatures and closes a locking circuit for itself from ground, armature and front contact of relay 71, which is operated at this time as has been described, left 65 hand winding of relay 50, brush 116 of the

allotter, conductor 117, winding of relay 103 to grounded battery. The relay 103 when operated closes an energizing circuit from ground, its lower-most armature and front contact, winding of relay 88, and resistance to grounded battery. The relay 88 attracts its armatures and thereby closes a break point in the holding circuit of the called line switch.

As soon as the relay 62 attracted its armatures, it closed a circuit for the line relay LR' of the called line from grounded battery, lower winding of this relay, upper-most front contact and armature of relay 62, upper-most back contact and armature of cut-off relay CO', to ground over conductor 59. As soon as the line relay LR' attracts its armatures, it closes a locking circuit for itself from grounded battery, its lower winding, upper-most front contact and armature of relay 62, upper-most back contact and armature of cut-off relay CO', conductor 61, inner-most front contact and armature of relay 62, lower-most front contact and armature of the line relay LR', lower-most continuity spring and contact of cut-off relay CO' to ground. When the line relay LR' operated, a locking circuit is closed for the relay 62, from grounded battery, winding of relay 71, conductor 72, upper winding, front contact and armature of relay 62, conductor 73, lower-most front contact and armature of line relay LR' to ground at the continuity spring and contact of relay CO'. The operation of the line relay LR' prepares an operating circuit for the motor magnet MM of the called line switch or trunk selector switch. This circuit is traceable from grounded battery, resistance, back contact, armature and winding of the motor magnet MM, conductor 74, lower-most front contact and armature of line relay LR', continuity spring and contact of cut-off relay CO' to ground. Under the control of this circuit the called line switch or trunk selector advances its brushes 75, 76, 77, 78 and 79 until the trunk test brush 79 which is now effective because of the closures of the lower contact and armature of relay 62 locates the idle trunk link that has been designated by the allotter switch. When a designated trunk line is located, a circuit is closed from grounded battery, resistance, back contact and armature of the motor magnet MM of the called line switch, lower winding of the cut-off relay CO', conductor 80, inner armature and front contact of line relay LR', lower armature and front contact of relay 62, trunk test brush 79, contact 81, conductor 82, allotter brush 83, conductor 84, front contact and armature of relay 64 to ground, which circuit functions to stop the switch and operate relay CO'. When the cut-off relay CO' is operated it causes relay LR' of the called line to de-energize and closes

100

105

110

115

120

125

130

a circuit for itself from ground, through its upper winding, inner upper front contact and armature, conductor 85, brush 75, contact 86, conductor 87, through contact 5 and armature of relay 88, winding of relay 67 to grounded battery. The cut-off relay CO and relay 62 are locked operated in multiple, and the relay 67 is energized in this circuit. The relay 67 attracts its armatures 10 and at its left hand front contact and armature closes a circuit from grounded battery, resistance, winding of the ringing relay RING, front contact and armature of relay 67, back contact and armature of relay 68 15 to ground. Relay RING attracts its armatures and closes a ringing circuit from the ringing machine 90 which is common to the exchange, upper winding of the trip relay, right hand front contact and armature of 20 the ringing relay, conductor 91, contact 93, ring brush 76, through the bell at the called substation, tip brush 77, contact 92, conductor 94, low resistance, left hand front contact of relay RING, inner right hand 25 armature and front contact of relay 67 to ground. By reason of the low resistance last mentioned a current is induced in the circuit including conductors 108 and 109, leading to the calling substation with the 30 result that the calling subscriber hears a tone indicating that the wanted party is being signaled. Ringing current is intermittently applied to the called subscriber's circuit until the called subscriber responds by removing 35 his receiver from its switchhook, whereupon the trip relay TRIP attracts its armatures and at its upper armature short circuits the ringing relay RING. At the lower armature and front contact of the trip relay, a locking circuit is closed through its lower winding, armature and front contact, armature and back contact of the ringing relay RING, inner right hand front contact and armature of relay 67 to ground. 40 When relay 67 was operated it opened at its left hand armature and back contact the circuit for holding the relays 64 of Fig. 2 and 56 of Fig. 3 operated. With the relay 64 de-energized, the ground potential 45 for stopping the line switches associated with the allotted link circuit is now transferred from the test circuit of the called trunk selecting switch to that of the calling trunk selecting switch. When relay 56 de- 50 energizes, it opens the circuit which has been holding the sender holding relay 15 energized, and also the relays CO and 10 and the first named relay immediately retract their armatures, but the slow releasing 55 relay 10 has a holding circuit prepared for it as will be described. The relay CO upon de-energizing disconnects the brushes 21 and 22 of its line or trunk selecting switch from the sender which it has previously seized, and the calling line is again con-

nected to its line relay LR, causing this relay to attract its armatures to operate the busy relay 71.

When the circuit to the brushes 21 and 22 of the called line switch is opened, the impulse relay IMP de-energizes and shortly afterward the slow releasing relay 20 retracts its armature to complete a self-interrupting circuit for the motor magnet MM of the tens register, its armature and back 75 contact, brush 19 in its off normal position, back contact and armature of relay 20, back contact and armature of relay IMP to ground. The motor magnet MM continues to advance its brushes until brush 19 reaches its normal 80 contact, whereupon the operating circuit just described is interrupted. A circuit is now closed for restoring the units register, this circuit being described from ground, armature and back contact of relay IMP, 85 armature and back contact of relay 20, brush 19 in its normal position, conductor 18, brush 17 in its off normal position, back contact, armature and winding of the motor magnet MM of the units register to grounded battery. Under the control of this circuit the units register is advanced until it reaches its normal position. Relays 33 and 39 are de-energized because the releasing ground at 90 relay IMP short circuits them. 95

With the line relay LR operated the motor magnet MM of the calling line switch advances its brushes to seize the other end of the link circuit with which the called line switch is in engagement. During this second operation of the calling line switch, the testing operation is under the control of the trunk test brush 97, since the relay 10 was locked energized after its previous holding circuit was interrupted by the relay 56. 100 A substitute holding circuit for the relay 10 is immediately completed by the re-energization of the line relay LR and may be traced from grounded battery, winding of relay 71 at the extreme right of Fig. 2, conductors 72 and 98, right hand winding of relay 10, its inner right hand front contact and armature, inner front contact of the line relay LR, conductor 8, continuity spring and contact 6 to ground. When the allotted link 110 is reached, the motor magnet MM is shunted by a circuit from grounded battery, resistance, back contact and armature of the motor magnet MM, upper winding of the cut-off relay, conductor 9, upper armature and front 115 contact of relay LR, left hand armature and front contact of relay 10, brush 97, test contact 99, conductor 100, allotter brush 95, back contact and armature of relay 64 to ground. The cut-off relay is energized in 120 this circuit and attracts its armature to complete a holding circuit for itself from ground, its lower winding, and in multiple therewith a circuit for relay 10, its lower winding, front contact and armature of relay CO, 130

holding brush 23, contact 101, conductor 102, inner armature and front contact of slow releasing relay 103, winding of relay 110 to grounded battery. As soon as the cut-off relay again attracted its armatures it connected the calling line to brushes 21 and 22 and closed a circuit including both sides of the calling line and both windings of the battery feed relay 104. This relay is now operated and attracts its armature to close a substitute energizing circuit for the relay 103 and thereby shunts the relay 50, causing it to de-energize. When the relay 110 attracts its armature, it closes a circuit from ground, right hand armature and front contact of the relay 100, conductor 106, allotter brush 107, back contact, armature and winding of the motor magnet MM of the allotter, and upper winding of the resistance unit 32 to grounded battery. Under the control of this circuit the motor magnet MM advances the allotter brushes one step and if the contact 108 individual to the next link circuit is busy, the motor magnet MM will continue to advance its brushes until an idle link circuit is found.

Talking battery for the calling subscriber is supplied through the windings of relay 104, while talking battery for the called subscriber is supplied through the windings of the relay 68.

In the foregoing description it was assumed that the called line was idle. It will now be assumed that the called line is busy under which condition the cut-off relay CO' individual to this line will have its armatures attracted so that when the multi-contact relay 54 is operated, the conductor 59 extended to the called line switch circuit will be open at contact 60. The relays 62 and LR' of the called line cannot be operated due to the fact that this contact 60 is open. The relay 67 therefore cannot operate and will therefore not close the circuit to energize the ringing relay RING. Since the conductor 59 is open at the cut-off relay CO' of the called line at the moment when relay 46 is operated, no energizing circuit will be closed for relay 56, consequently no holding circuit will be completed for the sender holding relay 15, and it will be de-energized. The cut-off relay CO of the calling line will also be de-energized and re-connect the calling line to its line relay LR, whereupon the motor magnet MM of the calling line switch will advance its brushes to the link indicated by the allotter. As soon as this link is reached, the motor magnet is again shunted and the cut-off relay CO energizes over a circuit traceable from grounded battery, resistance, back contact and armature of the motor magnet MM of the calling line switch, upper winding of the cut-off relay CO, conductor 9, upper armature and front contact of line relay LR,

left hand armature and front contact of relay 10, trunk test brush 97, contact 99, conductor 100, allotter brush 95, back contact and armature of relay 64 (now de-energized), to ground. The cut-off relay 70 on attracting its armatures connects the line to its brushes 21 and 22, and thereby completes a circuit for the battery feed relay 104. This last named relay continues the operation of the slow releasing relay 103, which in turn controls the release of the calling switch. When the cut-off relay is operated, it closes a locking circuit for itself and in multiple therewith a circuit for the left hand winding of relay 10, armature 80 and front contact of relay CO, holding brush 23, contact 101, conductor 102, inner front contact and armature of relay 103, winding of relay 110 to grounded battery. Relay 110 attracts its armatures for a purpose to be described. Since the called line was engaged its line switch brushes are not moved into engagement with the trunk link indicated by the allotter, and therefore the called holding relay 67 will not be operated. Under these conditions a busy tone is transmitted from the busy machine BZ, left hand armature and front contact of relay 110, right hand back contact and armature of relay 67, condenser, conductor 108, contact 107, brush 21 through the substation circuits, brush 22, contact 106, conductor 109, right hand winding of relay 104 to battery. The calling subscriber on receiving the busy signal knows that the called line cannot be reached, so that he then replaces the receiver on the switchhook to effect the release which will now be described.

In the present system the releasing means are so arranged that the calling subscriber effects the release of his line switch and the called subscriber effects the release of the line switch individual to his line. When the calling subscriber replaces his receiver on its switchhook, the battery feeding relay 104 of Fig. 2 releases and shortly afterward the slow releasing relay 103 de-energizes. When relay 103 retracts its armature, the holding circuit serially including the relay 110 and the relays 10 and CO is opened permitting these relays to release. At the upper armatures and front contacts of the relay CO the brushes 21 and 22 of the calling line switch are disconnected from this line so that the brushes of this line switch may remain in engagement with the link just used.

When the called subscriber replaces his receiver on its switchhook, his battery feeding relay 68 releases its armature and shortly afterwards the slow releasing relay 88 retracts its armature. When relay 88 de-energizes, it opens the holding circuit including relays 67, CO' and 62, and these relays de-energize. At the lower armatures and front contact of relay CO', the brushes 130

76 and 77 of the called line switch are disconnected from this line. The called line switch also remains in engagement with the terminals of the link last used. It will be noted that the test conductor 106 leading to the allotter is connected to a busy potential either at the front contact and armature of relay 110, or at the front contact and armature of relay 68 as long as either calling or called subscribers are holding this trunk circuit. As soon as the relay 67 de-energizes, it opens the locking circuit of the trip relay TRIP, and this relay restores to normal.

If the called subscriber restores his receiver on its switchhook before the calling subscriber attempts to effect the release, the relay 68 will de-energize as before described, but there is still an operating circuit for the slow releasing relay 88 at the lower-most front contact and armature of relay 103. Under these conditions the slow releasing relay 88 is de-energized by reason of a shunt circuit extended from grounded battery, resistance, upper contact and armature of relay TRIP still energized, back contact and armature of relay 68 to ground. When relay 88 is thus de-energized, the holding circuit including the relay 67 is interrupted and the called line switch is made ready for the next call in the manner previously described.

The present arrangement is so arranged that if either the calling or called subscriber does not replace his receiver on its switchhook when the other party to the connection has released, a busy tone is transmitted to the subscriber maintaining the connection. If the calling party restores his receiver to its switchhook, the relays 104, 103 and 110 will be de-energized in the manner previously described, at which time the circuit is closed from the busy device BZ, armature and back contact of relay 110, outer right front contact and armature of relay 67, over conductor 94 to the called subscriber's line and conductor 91. If the calling party maintains the connection after the called party has released, relays 103, 104 and 110 will be held energized while relays 68, 67 and 88 will be de-energized. Under these conditions a busy tone will be transmitted from the busy device, left hand armature and front contact of relay 110, back contact and armature of relay 67, conductor 108 to the calling substation, conductor 109, and winding of relay 104 to grounded battery.

If the subscriber B at substation 89 desires to establish connection to subscriber A whose station is designated 88, shown at the upper left hand corner of Fig. 1, the subscriber at station 89 seizes an idle sender whereupon the tens register will advance eight steps, and the units register will also be advanced eight steps under which condi-

tions the relay 54 (Fig. 3) will again be energized, but this time its contact 119 will be effective to extend the starting circuit 118 to the line relay LR and relay 10 of the substation 88. The remaining operations will be effective in a manner similar to that previously described.

At the lower left hand corner of Fig. 2 there is shown an operator's telephone. In the ordinary use of the present system this operator's telephone is not necessary. However, if the calling subscriber fails to operate his dial within a reasonable time, the signal lamp 124 burns steadily, and the operator by throwing her listening key LK will connect her telephone set to the calling line to ascertain the number of the wanted line. Thereupon she operates her dial 119 to intermittently close a circuit from ground over conductor 120, contact of the listening key, conductor 121, armature and front contact of relay 20, back contact and armature of relay 33, winding of the motor magnet MM of the tens register to ground. Under the control of this circuit the motor magnet MM advances the brushes of the tens register to store up the tens designation of the wanted line. The relay IMP is held energized all during this time over a circuit including a calling subscriber's line, and the relay 20 is held energized at the armature and front contact of this last named relay. The operating circuit for the relay 36 extends from grounded battery, winding of this relay, left hand front contact and armature of relay 20 to ground over conductor 121. The relay 36 is held operated during this series of impulses, but at the termination thereof retracts its armature to bring about the energization of the switching relay 33, whereupon the impulses transmitted over the conductor 121 are transmitted to the motor magnet of the units register. When the subscriber dials or the operator throws key LK, relay 123 operates and locks itself operated to extinguish lamp 124. The remaining operations take place in the manner previously outlined.

The operator's telephone set also becomes effective if it is desired to omit the dial impulse senders from certain of the substations. Under these conditions the calling subscriber on removing his receiver from its switchhook, will thereby cause his line switch to seize an idle sender similar to that shown in Figs. 2 and 3. It will be assumed that the sender of these figures has been seized. The impulse relay IMP will be operated over conductors 29 and 30 and will attract its armatures to close an operating circuit for the slow releasing relay 20. This last named relay attracts its armatures and at its inner right hand armature and front contact closes a circuit from ground over conductor 122, armature and back contact of

relay 123 to the operator's signal 124. Since the lamp burns steadily, the operator knows that she should attend to the call and she throws her listening key and requests the 5 wanted number. She thereupon operates the dial 119 as previously described to complete the wanted connection. The operation of the key, LK, energizes relay 123 which locks itself and puts out the lamp.

10 In the modifications shown in Fig. 4 the group of ten multi-contact relays, common to the exchange, has been replaced by an eleven brush rotary switch. With the exception of this substitution and of slight 15 changes in the circuit of the tens and units registers, the remainder of the system as well as the mode of operation remains unchanged and it will therefore not be necessary to describe the manner in which the 20 calling line switch seizes an idle sender, or how the wanted number is stored up in this sender, or how the called and calling line switches then seize the allotted trunk, and how the signaling and releasing functions 25 are performed. After the tens and units registers have been set, their relays IMP, 20, 33, 15, 39 and 26 will be held operated, and if the extended starter wire is in condition to permit the call stored on the sender of 30 Fig. 4 to be completed, the relay 46 will then be operated to bring about the completion of the call. Relay 46 is energized in a circuit closed from ground, its right hand winding, inner most upper front contact and armature of relay 26, outer armature and continuity spring of switching relay 39 to battery over conductor 125. Relay 46 attracts its armatures and at its left hand armature and front contact closes a locking circuit 40 over conductor 51 to ground at the upper armature and front contact of relay 26. At the inner right hand armature and front contact of relay 46, a circuit is closed through the motor magnet 127 of the eleven 45 brush switch, its armature and back contact, and resistance to grounded battery. Under the control of this circuit the motor magnet 127 advances the brushes of its switch until the test brush 112 engages the contact 113 50 which test contact is determined by the setting of the units register at which time the motor magnet 127 is shunted by a circuit now closed from grounded battery, resistance, test brush 112, test contact 113, contact 42 and brush 41 of the units register, winding of relay 114, outer right hand front contact and armature of relay 46 to ground. The relay 114 is operated in this circuit and 55 at its armature and back contact opens up the holding circuit for the slow releasing relay 26, which in turn shortly afterward interrupts the locking circuit of the relay 46, but before relay 46 is de-energized the starting circuit for the called line switch is 60 closed to ground over conductor 59, contact 65

111, brush 128, conductor 129, contact 35 and brush 34 of the units register, left hand winding of relay 56, front contact and armature of relay 114 to ground. The remaining operations of the system including 70 the operation of the called line switch and the release of the sender are accomplished in the manner previously outlined.

What I claim is:

1. In a telephone system, a plurality of 75 telephone lines, trunk selecting switches each having fixed contacts, movable wipers co-operating therewith and individual operating means for said wipers, said telephone lines terminating in said movable 80 wipers, a trunk circuit common to said lines terminating at fixed contacts in said switches, means for causing each trunk selecting switch to seize one end of said trunk when its associated line originates a call, 85 and means for causing each of said trunk selecting switches to seize the other end of said trunk circuit when its associated line is called.

2. In a telephone system, a plurality of 90 telephone lines, a trunk selecting switch individual to each of said lines, said trunk selecting switch being provided with fixed contacts, sets of wipers co-operating therewith and individual operating means for 95 each set of wipers, a plurality of trunk circuits common to said telephone lines, both ends of each trunk circuit terminating in fixed contacts of each trunk selecting switch, and means for actuating said trunk selecting switches to seize a trunk circuit in completing telephone calls.

3. In a telephone system, a plurality of 105 telephone lines, a trunk selecting switch individual to each of said lines, said trunk selecting switch having sets of fixed contacts, sets of movable wipers co-operating therewith and means individual to each switch for operating its set of wipers, a 110 plurality of trunk circuits, each trunk circuit having its ends conductively separated but inductively connected together, the ends of each of said trunk circuits terminating in fixed contacts of said trunk selecting switches, and means for operating said 115 trunk selecting switches in completing a call.

4. In a telephone system, a telephone line, a trunk selecting switch individual to said line, said trunk selecting switch being provided with fixed contacts, movable contacts co-operating therewith and separate operating means for each set of movable contacts, said telephone line terminating in said movable wipers, a trunk circuit terminating at two points in the fixed contacts of said switch, and means for advancing said 120 trunk selecting switch to one point when said line originates a call, and means for advancing said trunk selecting switch to the 125 130

other point when said telephone line receives a call.

5. In a telephone system, a plurality of telephone lines, trunk selecting switches for 5 said telephone lines, each of said switches having fixed contacts, movable wipers co-operating therewith and individual operating means for said wipers, said telephone lines terminating in the movable wipers of 10 a trunk selecting switch, a plurality of trunk circuits common to said lines and terminating in said fixed contacts, an allotter for assigning trunk circuits for use, means for causing each trunk selecting switch to seize 15 one end of an allotted trunk circuit when its associated line originates a call, and means for causing each trunk selecting switch to seize the other end of the allotted trunk when its associated line is called.

20 6. In a telephone system, a plurality of telephone lines, a trunk selecting switch for each of said lines, a plurality of trunk circuits and a plurality of sender circuits terminating in each of said trunk selecting switch- 25 es, a sender connected to each of said circuits for storing up the designation of wanted lines, means for variably setting said sender in response to impulses transmitted over its associated sender circuit, and means 30 operative in response to the setting of said sender for causing the trunk selecting switch of the wanted line to extend the connection.

7. In a telephone system, a plurality of telephone lines, a trunk selecting switch individual to each of said lines, a plurality of trunk circuits and a plurality of sender circuits terminating in each of said trunk selecting switches, a sender connected to each of said sender circuits, an allotter for 40 assigning trunk circuits for use, means for causing the trunk selecting switch of a calling line to seize an idle sender, means for variably setting said sender in response to impulses transmitted over its associated 45 sender circuit, means controlled by the setting of said sender for causing the trunk selecting switch individual to the wanted line to seize an allotted trunk, and means for extending the calling line to the allotted 50 trunk.

8. In a telephone system, a plurality of telephone lines, trunk selecting switches having fixed contacts and movable wipers in which a telephone line terminates, a plurality of trunk circuits terminating in said 55 fixed contacts, both ends of each of said trunk circuits terminating in each of said trunk selecting switches, and means for causing two trunk selecting switches to seize 60 a trunk in completing a connection between two telephone lines.

9. In a telephone system, a plurality of lines, a progressively movable rotary step by step line switch for each of said lines, a 65 plurality of trunk circuits, both ends of each

of said circuits terminating in each of said switches, and means to operate two rotary line switches to seize a trunk circuit in completing a connection between two telephone lines.

70

10. In a telephone system, a plurality of telephone lines, a trunk selecting switch for each line, a plurality of trunk circuits terminating in said switches, an allotter for assigning trunks for use, means controlled by 75 the allotter to cause a trunk selecting switch of the calling line to seize an allotted trunk, directly controlled means for initiating the operation of a trunk selecting switch of the called line, and means controlled by said 80 allotter for causing said last mentioned trunk selecting switch to seize said allotted trunk circuit.

11. In a telephone system, a plurality of telephone lines, a trunk selecting switch individual to each of said lines, a plurality of trunk circuits and a plurality of senders common to said telephone lines, means for causing a trunk selecting switch individual to a calling line to seize an idle sender on 85 the initiation of a call, means for variably adjusting a selected sender in response to impulses transmitted from the calling line, means controlled by the adjustment of said sender for causing the trunk selecting 90 switch of a wanted line to seize an idle trunk, means thereupon effective for causing the trunk selecting switch of the calling line to seize the same trunk, and means for effecting the release of said sender before the 100 dis-establishment of the telephone connection.

12. In a telephone system, an incoming line, a plurality of outgoing lines, means including an automatic switch for extending said incoming line to a wanted outgoing line, a sender for controlling the operation of said automatic switch, means responsive to impulses over said incoming line for variably adjusting said sender, an operator's position also arranged to control the setting of said automatic switch, means for signaling said operator's position in response to the initiation of a call on said incoming line, and means for disabling said 110 signaling means controlled by impulses over said incoming line.

13. In a telephone system, an incoming line, a plurality of outgoing lines, means including an automatic switch for extending 120 said incoming line to a wanted outgoing line, a sender selectively adjusted by impulses over said incoming line to control the setting of said automatic switch, means for connecting said sender to said incoming 125 line, an operator's position, and means for signaling said position when no impulses are transmitted to said sender after its seizure.

14. In a telephone system, an incoming 130

line, a plurality of senders, means for extending said incoming line to an idle sender, an operator's position and a signal associated therewith, means for actuating said signal on the seizure of any of said senders, means controlled by the transmission of impulses over said incoming line for disabling the actuating means of said signal, and automatic means controlled by said sender for 10 extending said incoming line to a desired outgoing line.

15. In a telephone system, an incoming line, a plurality of outgoing lines, an automatic switch for extending said incoming line to a desired outgoing line, subscriber controlled means including a register sender and operator controlled means for causing said automatic switch to extend said incoming line to a desired outgoing line, said subscriber controlled means being normally effective to control the operation, a signal for indicating the necessity of using the operator controlled means, and discriminating means for controlling said signal.

25. 16. In a telephone system, a plurality of telephone lines, certain of said lines being provided with impulse transmitting devices, a register sender arranged to be variably controlled over a telephone line in response to the operation of said impulse transmitting device, means including automatic switches for interconnecting any one of said lines with any of the other lines, said automatic switches being controlled in accordance with the setting of said register sender, an operator controlled transmitting device for causing said automatic switches to interconnect a telephone line to any of the other lines, and a signal for indicating that 30 the operator's transmitting device must be used in completing a connection, and means for disabling said signal.

45. 17. In an automatic telephone system, a plurality of telephone lines, switches individual to each telephone line, a plurality of trunk circuits accessible to each switch, a plurality of senders each comprising a plurality of step by step register switches, means including the individual switch of a 50 calling line for connecting said telephone line to an idle register sender and to an idle trunk circuit, means controlled over said lines for variably and selectively adjusting the selected register sender, a test circuit for each telephone line and means including the adjusted sender for controlling the completion of the test circuit to the called line to cause its individual line switch to complete a telephonic connection between the 55 calling and called lines over a selected trunk circuit.

60. 18. In an automatic telephone system, a plurality of telephone lines, a plurality of trunk circuits, progressively movable non-numerical switches associated with said

telephone lines for connecting the telephone lines to idle trunk circuits, a plurality of senders each comprising a plurality of step by step register switches, means for connecting a calling telephone line to an idle sender, 70 said means including a non-numerical switch, means controlled over said telephone line for selectively and variably adjusting the register switches of a selected sender, a starting circuit for each telephone line for initiating the operation of the non-numerical switch associated with a line to seize a selected trunk circuit when it is called and means including the adjusted register sender for completing the starting circuit of the 75 wanted line.

19. In a telephone system, a plurality of incoming circuits, a plurality of non-numerical switches each provided with fixed contacts, movable contacts co-operating 85 therewith and separate operating means for the movable contacts of each switch, each incoming circuit terminating in the movable contacts of a non-numerical switch, a plurality of trunk circuits, the ends of each 90 trunk circuit terminating in the fixed contacts of non-numerical switches and sender means each including rotary register switches for causing the switches associated with two incoming circuits to complete a 95 telephonic connection between said last mentioned circuits over a selected trunk circuit.

20. In a telephone system, a plurality of telephone lines, a plurality of non-numerical switches each provided with fixed contacts, 100 movable contacts and separate operating means for each switch, trunk circuits terminating in said fixed contacts, each telephone line terminating in the movable contacts of a non-numerical switch, a plurality 105 of senders each including a plurality of register switches arranged to be adjusted in succession and means including the calling telephone line and the contacts of a non-numerical switch for adjusting said 110 register switches, a circuit completed under the control of said registers for causing the non-numerical switch associated with the called line to seize a trunk circuit and thereby complete a telephonic circuit between the 115 calling and called lines through the non-numerical switches associated with these lines.

21. In a telephone system, a plurality of telephone lines a trunk selecting switch associated with each of said lines, a plurality of trunk circuits terminating in said switches, a sender accessible to said telephone lines and including a plurality of register switches arranged to be variably controlled over a calling telephone line, means for causing the trunk selecting switch associated with the calling line to seize a trunk circuit, a test circuit for each telephone line, a group of relays common to said tele- 130

phone lines and co-operating with said register sender for completing the test circuit of the called line and means including said test circuit for causing the trunk selecting switch associated with the called line to seize a trunk circuit whereby the calling and called telephone lines may be telephonically connected to a trunk circuit by means of the trunk selecting switches associated with these telephone lines.

22. In an automatic telephone system, a plurality of incoming circuits, a non-numerical switch for each incoming circuit, trunk circuits terminating in said non-numerical switches, means to cause a calling incoming circuit to seize an idle trunk circuit, a register sender common to said in-

coming circuits and including a plurality of rotatable switches arranged to be variably adjusted in succession over any of said incoming circuits to designate any other incoming circuit as a wanted incoming circuit, a plurality of starting circuits, a group of multi-contact relays common to said incoming circuits and operating with said rotary switches to complete a starting circuit of a wanted incoming circuit and thereby cause the non-numerical switch of said wanted incoming circuit to seize the selected trunk circuit.

In witness whereof, I hereunto subscribe my name this 16th day of February, A. D. 1920.

WINFRED T. POWELL.
